CLAIM

The ornamental design for bulk seed transport bin, as shown and described.

DESCRIPTION

FIG. 1 is a perspective view of the bulk seed transport bin of the present invention;

FIG. 2 is a front elevation view of the bin;

FIG. 3 is a rear elevation view of the bin;

FIG. 4 is a side elevation view of the bin; and,

FIG. 5 is a top plan view of the bin.

The broken lines shown in all views are for illustrative purposes only and form no part of the claimed design.

FIG.1

FIG.2

FIG.3

FIG.4
